UNITED STATES PATENT OFFICE.

GUISTO BOGGIO, OF ROYALTON, ILLINOIS.

BOTTLE CLOSURE.

Application filed June 9, 1922. Serial No. 567,137.

To all whom it may concern:

Be it known that I, GUISTO BOGGIO, residing at Royalton, in the county of Franklin and State of Illinois, have invented new and useful Improvements in Bottle Closures, of which the following is a specification.

My present invention has reference to a bottle closure.

My object is to produce a simple, cheap and effective means whereby a bottle may be 10 hermetically sealed by a closure which can be repeatedly used.

A further object is to arrange around the neck of a bottle a ring, to hingedly connect 15 to the ring a metal cap having a cork insert and to also connect the cap and ring by a spring which exerts a sufficient pressure between the insert and the mouth of the bottle neck as to prevent entrance of outside 20 air thereto.

The drawing which accompanies and forms part of this application, illustrates a satisfactory embodiment of the improvement reduced to practice, and wherein:—

25 Figure 1 is a perspective view illustrating the application of the improvement.

Figure 2 is a sectional view through the bottle neck in a line with the spring and the hinged connection between the closure and the ring on the neck of the bottle.

Referring now to the drawing in detail, the numeral 1 designates the neck portion of a bottle of the ordinary construction, the same having an outwardly bulged portion adjacent to its mouth. Arranged around the neck and held against downward movement by the flared contour of the neck and against outward movement by the referred to bulged portion 2 there is a ring 3. The ring has 35 hingedly connected thereto as at 4, a hook member 5. The hook has its beak passing through an opening 7 in the flange of a metallic closure 8. The closure is provided with a cork insert 9. The closure, at a point adjacent its connection with the hook is also 40 provided with an aperture through which is passed one hooked end of a coiled spring 10, the second hooked end being arranged around the ring 3.

The spring 10 provides a hinged connection for the cap. The hook 5 is formed from a single strand of wire having its body portion bent outwardly from its hinged connection with the ring 3 and from thence extended at an opposite angle to provide a handle portion 11. The handle, it will be noted by reference to the drawings, projects above the top of the cap or closure 8 when the latter is in sealing position. The handle is bent upon itself at its outer end and continued downwardly and from thence extended at an outward angle to provide the beak 6 of the hook. When in closed position the spring 10 exerts a pressure against the cap or closure 8 to force the same tightly 50 against the mouth of the bottle. The closure may be released by a sweeping movement of an operator's finger thereover to contact the handle 11 of the hook to bring the beak 6 thereof out of the opening 7 in the flange 70 of the closure.

Having described the invention, I claim:—

The combination with a bottle, of a closure therefor comprising a peripheral flanged member having a compressible insert, a ring around the neck of the vessel, a coiled spring having one end secured to the ring and its other end passing through the flange of the closure for establishing a hinged connection 75 between the closure and bottle, a hook member formed from a single strand of wire hingedly secured to the ring diametrically opposite the spring, said hook having its body portion arranged at an outward angle and from thence extended at an opposite angle to form a handle portion which is normally disposed above the top of the closure, said handle being bent upon itself 80 and continued rearwardly and from thence outwardly to form a beak, and the closure having its flange provided with an aperture receiving the beak of the hook therethrough.

45 In testimony whereof I affix my signature.

GUISTO BOGGIO.
